UNITED STATES PATENT OFFICE

2,504,796

ADJUSTABLE-ANGLE PIVOT-TYPE
ROD JOINT

Raymond Daley Boyd, San Antonio, Tex.

Application March 11, 1947, Serial No. 733,895

2 Claims. (Cl. 287—14)

1

This invention relates to tools and more particularly to those of the wrench type and especially those pertaining to shank extensions employed with same to manipulate bolts or nuts disposed in hard-of-access locations.

It is an object of the present invention to provide a new and improved wrench shank that will avoid one or more of the disadvantages and limitations of the prior art.

Another object of the invention is to provide a new and improved wrench shank that will afford a strong form of holder for the replaceable socket heads used in connection therewith.

A further object of the herein described invention is to provide a new and improved wrench that will permit the operating head used therewith to be readily manipulated for replacement and also to be held substantially in position when in use.

Other objects will become apparent as the invention is more fully set forth.

In order to clarify this invention and explain the principles thereof, reference is made to the appended drawings and the following description, wherein a particular form of the invention is outlined by way of example, while the claims particularly point out the scope of the invention.

In the drawings shown:

Figure 1 is a side elevational view of a wrench shank embodying this invention;

Figure 2 is a plan view of Figure 1; and

Figure 3 is an end view of Figure 2.

Similar reference characters refer to similar parts throughout the drawings.

In the construction indicated in the drawings, 10 represents the shank extension of a wrench of conventional form. One end portion 11 is swaged out or enlarged and provided with a polygonal recess 12 into which the tongue of a preceding wrench shank (not shown) is inserted to operate it. The other end portion 13 of the shank extension 10 is also swaged out to form a bifurcated jaw internally arcuate and laterally open on opposite sides to permit the insertions and rotation of an operable head 14 adaptable with a male end socket-engaging projection 15 for insertion in a socket to be rotated thereby. The head 14 has a rounded rib 17 straddled over its peripheral surface 18 and arranged to fit at its back and sides into an arcuate groove 19 provided in the shank 10. The head 14 has two sides 20 flat and fitted close against the inner side surfaces 21 of the jaw 13 which serve to restrain it from turning inside the jaw. The jaw

2

13 however holds it bodily and allows it to rotate when the shank extension is turned. A passage 22 runs transversely through the jaw sides and aligns with a passage 23 in the head 14 so that a pin 26 of cylindrical contour may be passed through both to hold them together as a unit. The projection 15 has a conventional ball lock 24 arranged to secure it to the socket of the extension that the projection may be attached to at the time. Likewise a ball lock 25 is provided in the recess 12 for a similar purpose.

The removal of the head is readily performed by removing the pin 26 and withdrawing the operable head 14 from between sides 21 of the jaw

13. The rib 17, which is preferably knurled, facilitates this operation, as it enables the head to be readily grasped between the fingers of the operator. The head may be rotated on the pin 26 through an arc as long as that of the rib 17 and at the same time be substantially held within the jaw 13. This jaw also distributes the stresses exerted on the head to the shank proper and relieves the sides 21 and pin 26 from having to take care of all the torsional pressure placed upon it.

The knurling on the rib 17 does not interfere with the rotation of the head 14 in the groove 19 as there is sufficient clearance to permit this. A ball lock 34 fits into indentations 35 in rib 17. The pin 26 holds the head properly positioned in the jaw 13 to provide the clearance at the groove 19.

While but one general form of the invention is shown in the drawings and described in the specifications, it is not desired to limit this application for patent to this particular form or in any other way otherwise than limited by the scope thereof, as it is appreciated that other forms of construction could be made that would use the same principles and come within the scope of the appended claims:

Having thus described the invention; what is claimed is:

1. A hinged joint comprising a shank having an enlarged end portion provided with a U-shaped slot forming spaced ears having confronting parallel surfaces, said surfaces merging into a transverse surface of said shank and forming the bottom of said U-shaped slot, said transverse surface being transversely concave, axially aligned pivot means provided in said ears, an arcuate transversely extending slot formed in said concave surface, said arcuate slot and said concave surface having centers of curvature lying on the axis of said pivot means, a head member having parallel sides engaging said confronting ear surfaces, and

having a curved peripheral surface complementary to the concave surface of said shank and to the bottom portion of said U-shaped slot, said pivot means mounting said head member for oscillatory movement with respect to said shank, and said head member being provided on its U-shaped periphery with a reinforcing rib, said rib lying in a plane midway between said parallel sides and extending into said arcuate slot, said rib and arcuate slot being complementary in cross-sectional size to thereby prevent excessive torsional strain on said pivot means.

2. In the hinged joint described in claim 1, spaced indentations provided in said rib, and a

ball lock positioned in said arcuate slot to engage a selected indentation to frictionally hold said head member in a selected position.

RAYMOND DALEY BOYD.
